[57] **CLAIM**

The ornamental design for a wireless communication system and flagpole, as shown and described.

DESCRIPTION

FIG. 1 is a front elevational view of a wireless communication system and flagpole showing my new design;

FIG. 2 is a rear elevational view thereof;

FIG. 3 is right side elevational view thereof;

FIG. 4 is left side elevational view thereof;

FIG. 5 is a top plan view thereof;

FIG. 6 is a front elevational view of a second embodiment of FIG. 1;

FIG. 7 is a rear elevational view thereof;

FIG. 8 is right side elevational view thereof;

FIG. 9 is left side elevational view thereof; and,

FIG. 10 is a top plan view thereof.

The showing of the flag in broken lines is for illustrative purposes only and forms no part of the claimed design.
